Adolfo Design Small Wig Travel Box with Top Handle, reviewed May 27, 2021 [online], [site visited]. Available from internet, URL: <<https://www.amazon.com/Travel-Shoulder-Carrying-Removable-Head-Holding/dp/B08FHFTGZL>> (Year: 2021).*

Primary Examiner — Kevin K Rudzinski*Assistant Examiner* — Amber J Rabie(74) *Attorney, Agent, or Firm* — Dunlap Bennett & Ludwig, PLLC(57) **CLAIM**

The ornamental design for a wig case, as shown and described.

DESCRIPTION

FIG. 1 is a perspective view of the wig case showing my new design in an open condition;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the wig case in a closed condition.

The broken lines shown in the drawings illustrate portions of the wig case that form no part of the claimed design.

1 Claim, 5 Drawing Sheets(56)
